GRINDING APPARATUS

Filed April 30, 1929

Inventor

Carter C. Gibson

By Watson E. Coleman Attorney

UNITED STATES PATENT OFFICE

CARTER C. GIBSON, OF HAMBURG, IOWA, ASSIGNOR TO THE TWO-WAY ELECTRIC GRINDER COMPANY, OF HAMBURG, IOWA, A CORPORATION OF IOWA

GRINDING APPARATUS

Application filed April 30, 1929. Serial No. 359,380.

This invention relates to a hollow grinding apparatus and more particularly to an attachment for use with grinding wheels for holding an element which is to be hollow ground against the peripheral edge of the wheel.

An important object of the invention is to provide in apparatus of this character a structure such that the angle of the element to be ground to the grinding wheel may be very finely regulated.

A further object of the invention is to provide in a device of this character a structure permitting blades of varying length to be ground while supporting the same at a predetermined angle to the periphery of the wheel.

A still further and more important object of the invention is to provide an apparatus particularly adapted for supporting the knives of meat grinders while hollow grinding the same.

These and other objects I attain by the construction shown in the accompanying drawings wherein for the purpose of illustration I have shown a preferred embodiment of my invention and wherein:

Figure 1 is a side elevation of grinding apparatus constructed in accordance with my invention, the dotted lines indicating the adjustment of the shaft during the grinding operation;

Figure 2 is an end elevation of the grinding apparatus partially in section;

Figure 3 is a section on line 3—3 of Figure 2;

Figure 4 is a section on line 4—4 of Figure 1.

Referring now more particularly to the drawing, the numeral 10 generally designates a suitably driven grinding wheel which may be of any desired material and 11 a support associated therewith. In the present disclosure the grinding wheel is indicated as of the motor driven portable type and the support 11 comprising a casing surrounding the motor which is not herein shown. In accordance with my invention, I provide upon the support 11 bearings 12, adapted to slidably receive a shaft 13, which parallels the axis

of grinding wheel 10. To the outer end of this shaft or that end adjacent the grinding wheel, I secure an arm generally designated at 14, this arm being formed in two sections 15 and 16, which are pivotally connected to one another, as indicated at 17. The inner end of one of the arm sections is formed as a segmental worm gear 18, while upon the other of the arm sections is rotatably mounted a worm 19 for coaction with the gear 18.

This shaft has at one end an operating head 20 in the form of a knurled disc whereby it may be rotated and, the relative position of the arm sections 15 and 16 may be varied, and the effective length of the arm 14 thus controlled. The outer end of the free or outer section 16 has secured to one side edge thereof an outstanding extension 21 which tapers and which toward its outer end has a stud-like projection 22 upon which is mounted a thumb nut 23 and a washer 24. The side edges 25 of the tapering projection are preferably beveled to form a spade edge, as indicated. This projection is adapted to extend into the central squared opening 26 of the knife 27 of a meat grinder and is adapted to extend diagonally thereacross with the spade edges 25 in engagement with the corners thereof. By use of the thumb nut the knife 27 can be very firmly forced down upon the extension 21 so that the blade is locked in position upon the arm. The position of the extension 21 with relation to the arm will be largely determined by the position of the blade sections 28 or blade 27. In the present instance, these blade sections are shown as aligning with the diagonals of the opening and accordingly, when the extension 21 is engaged, as above described, the blades aligned therewith will extend parallel to the shaft 13 and accordingly to the axis of the grinding wheel 10, which is the proper position for grinding.

It will be obvious that by varying the effective length of the arm, the angle of the face of the blade to the periphery of the wheel may be varied and it will also be obvious that the angular displacement of the sections of the arm will assist in providing this angular variation.

Therefore, by adjusting worm 19, the desired angle can be obtained when the blade can be brought into engagement with the edge of the rotating wheel, shaft 13 shifted longitudinally will cause the blade to travel longitudinally upon this edge of the wheel, and the grinding thus accomplished.

While I have in the present instance designated this specific support for use in maintaining a specific type of implement which is to be hollow ground in proper position for engagement with the grinding wheel, it will, of course, be obvious that this supporting means will be varied to enable use of the apparatus in other hollow grinding operations where desired.

It will also be obvious that other changes are possible in the construction hereinbefore set forth and I accordingly do not limit myself thereto except as hereinafter claimed.

20 I claim:-

1. In combination with a rotating grinding disc, a shaft axially paralleling the disc and mounted for rotation and longitudinal shifting, an arm carried by the shaft, said arm being formed in two sections, one of which is provided with a worm gear and the other of which is provided with a worm for coaction with the gear, the outer end of the outer section of the arm having a flat tapered extension provided with a stud, and a thumb nut mounted upon said stud.

2. In combination with a rotating grinding disc, a shaft axially paralleling the disc and mounted for rotation and longitudinal shifting, an arm carried by the shaft, said arm being formed in two sections, one of which is provided with a worm gear and the other of which is provided with a worm for coaction with the gear, the outer end of the outer section of the arm having a flat tapered extension provided with a stud, and a thumb nut mounted upon said stud, the sides of the tapered extension being formed with 45 spade edges.

In testimony whereof I hereunto affix my signature.

CARTER C. GIBSON.
